UNITED STATES PATENT OFFICE.

JOHN A. KILLIAN, OF DETROIT, MICHIGAN.

FLYING-MACHINE.

1,292,614.

Specification of Letters Patent.

Patented Jan. 28, 1919.

Application filed April 2, 1918. Serial No. 226,218.

To all whom it may concern:

Be it known that I, JOHN A. KILLIAN, a citizen of the United States, residing at Detroit, in the county of Wayne, State of Michigan, have invented certain new and useful Improvements in Flying-Machines; and I do hereby declare the following to be a full, clear, and exact description of the invention, such as will enable others skilled in the art to which it appertains to make and use the same.

The present invention relates to new and useful improvements in aeroplanes.

It is primarily the object of my invention to provide a means for increasing the stability of aeroplanes, particularly upon falling movement thereof, whereby the planes of the aeroplane may discharge a parachute function in such falling movement, to permit a proper landing of the aeroplane.

A further object is to increase the general stability of the aeroplane in normal flight, and to provide an arrangement of air engaging surfaces wherein the structure of the aeroplane may be simplified and considerably strengthened.

With the above and other objects and advantages in view, the invention resides more particularly in the novel combination, formation and arrangement of parts hereinafter described and particularly pointed out in the appended claims.

In the drawings:

Figure 1 is a perspective view of the improved aeroplane.

Fig. 2 is a front elevational view thereof.

Fig. 3 is a fragmentary sectional view at one side of the longitudinal central plane.

Fig. 4 is a detail sectional view on the line 4—4 of Fig. 3, showing the means for admitting air through the main plane.

Referring now more particularly to the drawings, there is provided a main plane 5, which is of generally oblong shape and which extends longitudinally of the machine, the front of this plane being taperingly reduced to a point. This plane is bowed upwardly, longitudinally thereof, and the curvature is gradually increased toward the rear portion of the plane whereby to exert a lifting action in the passage of the plane through the air in a general horizontal line. Depending from the central portion of the plane and extending longitudinally throughout its length is a stabilizing wall 6, the

lower edge of which is disposed below the side edges of the main plane and is connected therewith by a series of tie members 7. Supported in spaced relation above the main plane by standards 8 rising from intermediate portions of said plane is an auxiliary plane 9 having a curvature corresponding to the curvature of the main plane and of considerably lesser dimensions than the main plane whereby its edges are disposed inwardly of the edges thereof, this auxiliary plane being substantially square in shape. Extending between the two planes and forming substantially a projection of the wall 6 is a stabilizing wall 10.

In the structure thus described, the various planes and walls mutually brace each other to form an exceedingly simple and strong structure, and said planes further coact to afford a maximum flying efficiency and stability in the normal propulsion of the machine.

Formed in the intermediate portion of the main plane at the sides of the stabilizing wall 6 are a pair of openings 11 and these openings are normally closed by trap doors 12 hinged to the outer edges of the openings and controlled for opening and closing movements by rods 13 hinged to their inner side portions and hinged to a common handle rod 14.

Suspended below the stabilizing wall is a suitable car body 15, in which is positioned the engine 15^a for driving a tractor 16 carried by a shaft 17 journaled at the lower edge of the stabilizing wall 6 extending from a point above the car body to the forward end of said wall. The aeroplane is provided with front and rear elevating planes 18 and 19 respectively, and with a rudder 20.

To hold the trap doors 12 in normally closed position, the rod 14 is pivoted to the intermediate portion of the shank of a hook 21 which has its bill engageable in a keeper 22 on the car, whereby upon swinging said hook, the trap doors may be released and whereby they are normally held against force of wind pressure on the planes.

What is claimed is:

1. An aeroplane including a main supporting plane, an auxiliary supporting plane disposed above the main plane, a stabilizing wall disposed between the two planes and connected throughout its length to both

planes, the main plane being provided with openings at the sides of said wall, and means for closing said openings.

2. An aeroplane including a main supporting plane, an auxiliary supporting plane disposed above the main plane, a stabilizing wall between the two planes, a stabilizing wall depending from the main plane, in alinement with the wall above it, and a body carried under the main plane.

3. An aeroplane including a main supporting plane, an auxiliary supporting plane disposed above the main plane, a stabilizing wall between the two planes, a stabilizing wall depending from the main plane, a body carried under the main plane, openings in the main plane at the sides of the stabilizing walls and means for closing said openings.

20 4. An aeroplane including a main sup-

porting plane and an auxiliary supporting plane disposed above the main plane, and a vertical central wall between the two planes and connected thereto throughout its length, said main plane having openings on each side of said wall.

5. An aeroplane including a main supporting plane and an auxiliary supporting plane disposed above the main plane, and a vertical central wall between the two planes and connected thereto throughout its length, said main plane having openings on each side of said wall and means to open and close said openings at will.

In testimony whereof, I affix my signature, in the presence of two witnesses.

JOHN A. KILLIAN.
